UNITED STATES PATENT OFFICE.

CARL HAMBUECHEN, OF BELLEVILLE, ILLINOIS, ASSIGNOR, BY MESNE ASSIGNMENTS, TO NATIONAL CARBON COMPANY, INC., OF CLEVELAND, OHIO, A CORPORATION OF NEW YORK.

BATTERY HAND-LAMP.

1,365,988.

Specification of Letters Patent. Patented Jan. 18, 1921.

Application filed August 26, 1916. Serial No. 117,071.

To all whom it may concern:

Be it known that I, CARL HAMBUECHEN, a citizen of the United States, residing at Belleville, county of Saint Clair and State 5 of Illinois, have invented certain new and useful Improvements in Battery Hand-Lamps; and I do hereby declare the following to be a full, clear, and exact description of the invention, such as will enable 10 others skilled in the art to which it appertains to make and use the same.

It is the object of the present invention to provide a battery hand lamp, having improved switch mechanism and electrical connections for establishing and interrupting the flow of current from the battery to the lamp, the arrangement being such that accidental short circuiting of the battery or inadvertent lighting of the lamp is in large 20 measure prevented.

The objects and advantages of the present invention are made clear by the following description which is to be taken in conjunction with the accompanying drawings:

25 Figure 1 is a plan view of one embodiment of the invention;

Fig. 2 is a sectional elevation on the line 2—2 of Fig. 1;

30 Fig. 3 is an end elevation of the disk contact members which are interposed between the lamp and the battery;

Fig. 4 is a section through the disk contact members on the line 4—4 of Fig. 2;

35 Fig. 5 is a perspective view of the disk contact members;

Fig. 6 is a plan view of another embodiment of the invention wherein the casing is 40 of metal; and Fig. 7 is a longitudinal section of the embodiment shown in Fig. 6.

In the preferred embodiment, illustrated 45 in the drawings, the battery hand lamp is provided with a tubular casing 1, preferably of insulating material, and having threaded metal ends, provided as by the sleeves 2 and 3, secured to the insulating tube in the usual manner, as by the hollow rivets 4, Fig. 1. Secured to the base of the casing, as by threaded engagement with its sleeve 3, is a 50 metal cap 5 to which is attached, as by soldering, a helically coiled spring 6.

At the other end of casing 1 there is secured, as by threaded engagement with sleeve 2, a metal collar 7. A lens 8 and re-

flector 9 are supported at this end of the 55 tubular casing as by having their edges clamped between collar 7 and sleeve 2 in the usual manner. An incandescent, electric lamp 10 is secured to the reflector 9 as by having its base threaded therein, thereby 60 electrically connecting the outer terminal of the lamp with the metal reflector.

Within the tubular casing 1 is a dry 65 battery 11, preferably comprising a plurality of cells, arranged end to end as in ordinary practice and housed in a paste-board tube 12. The naked bottom of this battery rests on and makes electrical contact with the helically coiled spring 6.

When the tubular casing 1 is of insulating material, as above described, means are provided for maintaining electrical connection between spring 6 and the outer terminal of the lamp, as by permanently 70 mounting an electrical conductor 13 longitudinally of casing 1, and with its outwardly bent ends clamped beneath and contacting with the metal sleeves 2 and 3. This conductor 13 may be in the form of a narrow strip or ribbon and establishes a 75 permanent connection from the battery bottom through spring 6, cap 5, sleeve 3, ribbon 13, sleeve 2, and reflector 9 to the metal base of the lamp, and thereby to its outer 80 terminal.

The switch mechanism, whereby the flow of current from the battery to the lamp may be established or interrupted, comprises a base 14 of insulating material adjacent reflector 9 and preferably encircling the base 90 of the lamp as by being threaded to the exterior of the reflector, as shown in Fig. 2. This base may be of hard rubber, indurated fiber, or the like, and of circular shape, and supported wholly by the reflector. Secured 95 to this base 14 are a pair of contact members 15 and 16 which, in the preferred embodiment illustrated, are of dished form and spaced apart by an interposed layer of insulation 17. They may be secured together 100 and to the supporting base 14 by hollow rivets 18, the rivet holes in contact member 15 being large enough to prevent electrical connection through the rivets. One of these dished contact members is in electrical connection with the inner or central terminal 19 of the lamp, and the other is in electrical connection with the upper or inner terminal 105

20 of the battery. To establish a flow of current from the battery through the lamp, it is therefore only necessary to bridge the gap between the dished contact members 13 and 16. As a means for doing this, there is provided a contact blade 21, normally insulated from the battery and preferably in the form of a curved strip, housed within tubular casing 1 and slotted at 22 to slide 5 across the head of the supporting rivet 23. This contact blade may be attached by rivets to the thumb-piece 24 mounted, or positioned on the outside of the tubular casing about midway between its ends, and arranged to 10 slide longitudinally of the casing on a plate 25 riveted to the casing and slotted to permit movement of the rivets, whereby the thumb-piece is attached to the longitudinally moving contact blade.

15 To light the lamp, the thumb-piece 24 is pushed forward until contact blade 21 enters between and electrically connects contact members 15 and 16 by bridging the gap which normally separates them, and there- 20 upon current flows from battery terminal 20 through contact member 16, contact blade 21, and contact member 15 to the inner bat- 25 tery terminal 19, and thence through the lamp filament to the threaded outer ter- 30 minal of the lamp, finally returning through reflector 9, conductor 13, contact spring 6, and their associated parts to the naked bottom of the battery.

A battery hand lamp constructed as above 35 described has the advantage that the metal parts at the two ends of the casing are at the same electrical potential, viz., that of the lower battery terminal or bottom. It is therefore impossible to short circuit the battery 40 or cause an inadvertent lighting of the lamp by electrically connecting these two metal ends, as when the hand lamp is dropped into a wire basket or among metal tools. Similarly, thumb-piece 24 and its associated 45 metal parts are normally insulated from the battery, and the electrical connection of this thumb-piece with either of the metal ends, as by contact with a wrench in a tool kit, will not in any way establish a battery cir- 50 circuit. It is only when the thumb-piece 24 is pushed forward to light the lamp that its contact blade becomes a part of the battery circuit, and, under these conditions, the for- 55 ward portion of the contact finger is the only portion actively in circuit, and therefore this forward portion may, if desired, be insulated from the remainder and from thumb-piece 24 as by an insulating section introduced at 60 26. As shown in Figs. 6 and 7, the tubular casing 1' may be of metal with collars 2 and 3 integral therewith. In this form the conductor 13 is omitted entirely and the current is carried from spring 6 to reflector 9 through the metal casing 1'.

65 I am aware that various features of the

hand lamp described may be altered without departing from the spirit of my invention as particularly defined by the appended claims.

I claim:—

70

1. In a battery hand lamp, the combination of a casing, a battery and a lamp therein, means for connecting the bottom of said battery with the outer terminal of said lamp, and switch mechanism between the inner terminal of said lamp and the upper terminal of said battery, said mechanism comprising annular contact members positioned between the lamp and the battery, and a contact blade movable to connect said members when the lamp is to be lighted.

2. In a battery hand lamp, the combination of a tubular casing, a battery and a lamp therein, an insulating base encircling the base of said lamp, a pair of dished contact members spaced apart by insulating material and contacting, respectively, with the inner terminal of the lamp and upper terminal of the battery, and means for bridging the gap between said dished contact members when desired.

3. In a battery hand lamp, the combination of a tubular casing having threaded metal ends, a metal cap threaded to one of said ends and carrying a contact spring, a collar threaded to the other of said ends, a lens and a reflector held in position by said collar, a lamp secured to said reflector, a conductor electrically connecting said reflector with said metal cap, a battery with in said casing with its bottom contacting with said contact spring, a switch mechanism for connecting the inner terminal of said lamp with the upper battery terminal, said mechanism comprising a base of insulating material secured to said reflector, a pair of contact members spaced apart and secured to said base, said members being connected, respectively, with an upper battery terminal and with the inner lamp terminal, a contact blade mounted in said casing and insulated from said battery, said blade being adapted to slide longitudinally of said casing, to enter between and electrically connect said contact members, and a thumb-piece for slidingly actuating said contact blade when the lamp is to be lighted or extinguished.

4. In a battery hand lamp, the combination of a tubular casing having threaded metal ends, a metal cap threaded to one of said ends and carrying a helically coiled contact spring, a collar threaded to the other of said ends, a lens and a reflector clamped between said collar and the adjacent end of the tubular casing, a lamp threaded into said reflector, a metal strip electrically connecting said reflector with said metal cap, a battery within said casing with its bottom contacting with said heli-

- cally coiled contact spring, and switch mechanism for connecting the inner terminal of said lamp with the upper battery terminal, said mechanism comprising a circular base of insulating material threaded to and supported wholly by said reflector, a pair of dished contact members spaced apart, with insulation therebetween, said members being secured to said circular base 5 and contacting, respectively, with the upper battery terminal and with the inner lamp terminal, a contact blade mounted in said casing and insulated from said battery, said blade being adapted to slide longitudinally 10 of said casing, to enter between and electrically connect said dished contact members, and a thumb-piece for slidably actuating said contact blade when the lamp is to be lighted or extinguished.
- 15 5. In a battery hand lamp, the combination of a tubular casing of insulating material, a metal sleeve on each end thereof, a metal cap secured to one of said sleeves and carrying a contact spring, a collar secured to the other of said sleeves, a lens 20 and a reflector clamped between said collar and its sleeve, a lamp secured to said reflector, a conductor electrically connecting said reflector with said metal cap, a battery 25 within said casing with its bottom contacting with said contact spring, and switch mechanism for connecting the inner terminal of said lamp with the upper battery terminal, said mechanism comprising a base 30 of insulating material supported by said re- 35
- flector, a pair of contact members, spaced apart, with insulation therebetween, said members being secured to said base and connected, respectively, with the upper battery terminal and with the inner lamp terminal, a contact blade mounted in said casing and insulated from said battery, said blade being adapted to slide longitudinally of said casing, to enter between and electrically connect said contact members, and a thumb-piece mounted to slide longitudinally of said casing, said thumb-piece being attached to said contact blade to slidably actuate the same when the lamp is to be lighted or extinguished. 40
- 45 6. In a battery hand-lamp, two annular concentric contact members, electrical connection between one of said members and one terminal of the battery, a lamp interposed in said connection, electrical connection between the other of said members and the other terminal of the battery, and a switch for connecting said members. 50
- 55 7. In a battery hand-lamp, two annular concentric contact members, electrical connection between one of said members and one terminal of the battery, a lamp interposed in said connection, electrical connection between the other of said members and the other terminal of the battery, and a sliding switch-plate movable between said annular contact members into engagement therewith. 60
- 65 In testimony whereof I affix my signature.
CARL HAMBUECHEN.
